UNITED STATES PATENT OFFICE.

WILLIAM R. WILSON, OF AMITYVILLE, AND ARTHUR P. BROCKLEBANK, OF BROOKLYN, NEW YORK, ASSIGNEES TO WHEELER CONDENSER AND ENGINEERING COMPANY, OF NEW YORK, N. Y., A CORPORATION OF NEW JERSEY.

JET CONDENSER.

Application filed January 11, 1922. Serial No. 528,519.

To all whom it may concern:

Be it known that we, WILLIAM R. WILSON and ARTHUR P. BROCKLEBANK, citizens of the United States, and residents, respectively, of 5 Amityville and Brooklyn, in the counties of Suffolk and Kings and State of New York, have invented certain new and useful Improvements in Jet Condensers, of which the following is a specification, reference being 10 had therein to the accompanying drawing.

Our invention relates to an apparatus for the condensation of exhaust steam, the particular class being that of jet condensers either of the barometric type or of the low 15 level jet type with which a centrifugal removal pump is usually employed. One object we have in view among many that might be mentioned is to provide means for introducing the condensing water into the 20 chamber of condensation by subdividing it into a number of streams in such a manner that there may be a more thorough contact between the condensing water and the steam, and hence a quicker and more effective 25 condensation. The invention therefore may be said to consist essentially in the construction, arrangement and combination of parts, and in numerous details and peculiarities 30 thereof, substantially as will be hereinafter described and claimed.

In the accompanying drawings illustrating our invention:

Figure 1 is a vertical section of our improved jet condenser, taken on the line 1, 1, 35 of Figure 2.

Figure 2 is a horizontal sectional plan of the same, on the line 2, 2, of Figure 1.

Figure 3 is a horizontal detail section on the line 3, 3, of Figure 1.

Figure 4 is an enlarged detail section on the line 4, 4, of Figure 2, and

Figure 5 is another enlarged detail section on the line 5, 5, of Figure 2.

Similar characters of reference designate 40 corresponding parts throughout the different figures of the drawing.

1 denotes the main cylindrical condenser shell containing the chamber of condensation A. This shell is mounted on the tail-pipe 2, from which the water may be removed by a centrifugal or other pump, or pipe 2 may lead into a hot well, or be otherwise arranged for the discharge of its functions. Exhaust steam enters shell 1 through

the side inlet 3, while the injection waters 55 flow through pipe 5 and enter a supply chamber 4 supported on the top of the condensing chamber A. The water inlet 5 may be located at any desired point in the water supply chamber, that is to say on any part of 60 the same, and anywhere relatively to the shell and the steam inlet. The water chamber or box will probably be quite well filled with water all the time. The injection water passes from chamber 4 into chamber 65 A through the slotted bottom plate 8 of chamber 4, as I shall presently describe in detail, and falls from chamber 4 into and through the condensing chamber A in order that it may thoroughly commingle with and 70 condense the steam, the condensing water and the condensed steam falling into and passing off through the tail-pipe 2 and its connections. The air and non-condensable vapors are removed through the pipe or 75 passage 13 at one side of the shell 1, formed between the wall of the shell and a suspended plate 7, said passage having an outlet 6 by which a connection is made with the 80 vacuum or air removal pump.

The bottom plate or tray 8 of the water chamber 4 is formed with openings, slots, orifices, or passages, to permit the water to fall through into the condensing chamber A, and be split up into numerous parts, and 85 in the present example of our invention these openings take the form of elongated slots 9, preferably converging from the side of the shell where the exhaust steam inlet is located toward the air outlet 6, like the 90 ribs of a fan, so that the water may thus be introduced most directly and surely through these outlets into the chamber A. It will be noted that a considerable space of crescent shape is left at 17 between the ends of these 95 slots which are nearest the steam inlet and the adjacent wall of the water chamber, so that there will be a corresponding space at 15 in the chamber A between the ends of the sheets or streams of water and the steam inlet 3, and wall of the shell. This space 100 will be filled with steam in large quantity which will flow and feed around to the ends of the slots through the ends of the crescent shaped space 15, thus passing along the sides 105 of the shell from the widest to the narrowest parts of such space, so that an effective large distributing space for the steam is

provided, less and less steam being handled in such space as the narrow ends of the same are reached. The slots 9 are the widest nearest the exhaust inlet 3 where the steam enters 5 and they narrow down as they approach the air outlet 6 and as the steam is condensed. Each slot is therefore preferably made converging in width from one end to the other, the narrower end *b* being nearest air outlet 10 6 and the wider end *a* being nearest the exhaust inlet 3; and further each slot on its top chamber side, or the side which first receives the water, is made flaring or with beveled edges or sides that extend a substantial 15 distance through the thickness of plate 8, while the lower discharge sides of these slots are made with parallel edges or surfaces, as shown at *a'* in the widest end of the slot and at *b'* in the narrowest end of 20 the slot, see Figures 4 and 5. The wide receiving mouth of the slot enables the water to more quickly enter it, and the straight vertical parallel-sided discharge or outlet side permits a downward shoot or drop of 25 the water in a large voluminous sheet which has an extensive surface exposure to come into contact with the steam which is to be condensed. The sectional views of Figures 4 and 5 indicate how the slots 9 widen out 30 from one end to the other, and also how the beveled inlet side of the slot compares with the parallel-sided outlet edge. These radial slots in a series whose members are the longest in the middle and the shortest near 35 the sides, in combination with the steam distributing space constitute an important feature.

In addition to the series of radiating slots 9 which cover substantially the whole area 40 of plate 8, except the end part that covers the steam distributing space 15, leaving between and around them only enough of the plate to preserve its stability and strength to carry the weight of water that fills the 45 chamber 4, we find it convenient to further provide plate 8 with a few curved slots 10 arranged in one or more curved lines between the closely aggrouped narrower inner ends of slots 9 and the air outlet members 50 13 and 6, and close up against the partition 7 that forms the inner wall of air-outlet 13, said openings 10 however entering the condensation chamber A and not the air-passage 13, and being for the purpose of introducing curved segments of condensing water 55 just outside of the air outlet 13. Through these slots 10 a blanket or curtain of cold water falls transversely near the ends of the sheets which drop through the slots 9 and 60 this final curtain of cold water imparts a final cooling and condensing effect upon any steam left uncondensed in passing the rest of the condensing water, so that at the point nearest the air outlet the air and uncondensable vapors will be separated from the 65

water, and will pass off at the point 14 into air outlet pipe 13 and connection 6, while the water will fall downwardly through the shell and mingle with the other water passing out into the tail pipe. The ends of the 70 slots 10 are separated more or less by passages 16 which are at a different angle from the radial lanes between the slots 9, and this causes the steam passing through these converging radial lanes between the water sheets 75 from slots 9 to attack the segments of water falling through slots 10 diagonally and will not pass directly midway through the openings 16, so that in this way the cold water more effectually influences and condenses the 80 steam, in the final condensing process, and in the final air-separating and cooling effect. The steam which passes through the radial or converging lanes between the water sheets falling from slots 9 converges likewise and 85 reduces in volume as it flows towards the air outlet; corresponding thus to the reduced volume of water exposed to the steam.

The air-outlet 13, as already explained, is formed by the shell 1 and an inner curved 90 plate or wall 7 which projects downwardly alongside of the shell and is secured at its upper end by means of bolts 11 to the horizontal plate 8, the open lower end of passage 13 being indicated at 14 where the air 95 and non-condensable vapors are drawn by suction into the outlet 13. It may be further noted that the crown of the water chamber 4 is provided with one or more covered hand openings 12 to give access as required to the 100 interior of the chamber.

The operation can be very briefly set forth. The exhaust steam enters the inlet opening 3 and there fills and flows around through the space 15 in the side of the condensation chamber A, there coming into contact immediately with streams or sheets of water falling through slots 9 from chamber 4. These streams or sheets are the largest and have the greatest volume where they fall through the widest ends of openings 9, (which wide ends are nearest steam inlet 3), and into contact with them the steam comes immediately upon entering the shell. As the quantity of steam reduces in 110 volume, the sheets of condensing water which will be encountered will be gradually diminishing in width, as the smaller portions of the slots are approached, and the amount of water supplied through the narrower portions of the slots will be constantly 115 diminishing, so that by the time the steam reaches the entrance 14 into the air-withdrawal member, the steam will have virtually all been condensed, and the air and uncondensed vapors will readily be drawn into the vacuum of the dry vacuum connection after they have been released from the steam and water. The auxiliary slots 10 crossing the other slots 9 adjacent to the air outlet 120

furnish important cross-streams at this point and assist in the final cooling and disposal of air and uncondensable material.

Many changes may be made in the precise construction and combination of the various parts of our invention without exceeding the scope of the claims, particularly with reference to the number, size and character of the passages between the top water chamber and the condensing chamber for subdividing the condensing water into a plurality of sheets or streams, and we therefore reserve the liberty of modifying and changing the exact details of construction and combination as much as may be found necessary to adapt the invention for practical use in a great variety of places for which it is suited.

Having thus described our invention, what we claim as new and desire to secure by Letters Patent is:

1. In a jet condenser, the combination with a shell, having a steam inlet, and an air outlet, of an injection water inlet having a bottom provided with a plurality of slots converging towards the air outlet from a crescent shaped steam distributing space located in the shell near the steam inlet and partially extending around the ends of the slots, said crescent shaped steam space being located opposite to a similar space in the water chamber.

2. In a jet condenser, the combination with a shell having a steam inlet and an air outlet, of an injection water chamber having a bottom provided with a plurality of slots converging towards the air outlet, and an auxiliary transverse curved slot or slots adjacent to the air outlet to deliver final cooling water.

3. In a jet condenser, the combination of a shell having a condensing chamber provided with a steam inlet, and an inner vertical wall opposite the steam inlet and forming with the shell an interior air chamber receiving the air escaping from the condensing water

45

and the water of condensation, and having an air removal outlet, and an injection water inlet mounted on the shell and having a series of elongated slots radiating from a point near the air chamber and widening therefrom to the opposite end, so as to present the largest sheets of water at a point nearest to the steam inlet, together with slots arranged transversely to the elongated slots.

55

4. In a jet condenser, the combination of a shell having a condensing chamber provided with a steam inlet, and an inner vertical wall opposite the steam inlet and forming with the shell an interior air chamber receiving the air escaping from the condensing water and the water of condensation, and having an air removal outlet, and an injection water inlet mounted with the shell and having a plurality of openings or passages, each having beveled edges to provide a flaring mouth on the receiving side and a parallel-sided passage leading from such mouth to the discharge side of the opening.

60

5. In a jet condenser, the combination of a shell having a condensing chamber provided with a steam inlet, and an inner vertical wall opposite the steam inlet and forming with the shell an interior air chamber receiving the air escaping from the condensing water and the water of condensation, and having an air removal outlet, and an injection water inlet mounted with the shell and having a series of elongated slots radiating from a point near the air chamber and widening therefrom to the opposite end, so as to present the largest sheets of water at a point nearest to the steam inlet, together with a series of openings running cross-wise of said slots adjacent to the air chamber.
